UNITED STATES PATENT OFFICE.

ROBERT J. HARLEY, OF REED CITY, MICHIGAN.

MAIL-BAG RECEIVING AND DELIVERING APPARATUS.

1,141,793.

Specification of Letters Patent.

Patented June 1, 1915.

Application filed April 10, 1914. Serial No. 831,027.

To all whom it may concern:

Be it known that I, ROBERT J. HARLEY, a citizen of the United States, residing at Reed City, in the county of Osceola and State of Michigan, have invented new and useful Improvements in Mail-Bag Receiving and Delivering Apparatus, of which the following is a specification.

This invention relates to mail bag receiving and delivering apparatus; and it has for its primary object the provision of apparatus of this character in which the mail matter will be handled expeditiously and with the minimum possibility of its being injured during the collecting and delivering operation.

Another object of the invention is the provision of apparatus of this character which will consist respectively of receiving and delivering means adapted to be mounted at the station, and coöperating collecting and delivering means mounted on the car, and further, the provision of means on the car and means on the platform for rendering the device operative irrespective of the direction of movement of the car. In other words, I contemplate the provision of mechanism which may be rendered active where the rolling stock is adapted to travel on a single track.

Another object of the invention is the provision of collecting mechanism on the car and means carried thereby and adapted to be rendered active for an effective gripping of the bag immediately on the collecting operation.

A further object of the invention is the provision of receiving mechanism on the platform and means for normally holding the mechanism active to a collection of the bag from its coacting mechanism of the rolling stock, and further the construction of such means which may be actuated directly by the car and in successive order of the delivering of the bag.

A still further object of the invention is the provision of receiving and delivering mechanism which is mounted upon the car and disposed with such regard to the door opening as will permit said means to be readily moved in the direction of the opening for the manipulation of the mail bag.

With these and other objects in view, the

invention consists of certain novel features of construction, combination and arrangement of parts, as will be hereinafter described and claimed.

In the accompanying drawings: Figure 1 is a top plan view through a portion of a railway car, showing the application of the bag delivering and receiving devices thereto and illustrating an operative receiving position of the receiving device with the delivering device of the platform; Fig. 2 is a side elevation of a portion of a car provided with bag delivering and receiving devices in accordance with my invention. Fig. 3 is a horizontal sectional view on the plane indicated by the line 3—3 of Fig. 2 and showing the delivering device in operative position. Fig. 4 is a vertical longitudinal sectional view of the receiving device of the car. Fig. 5 is a similar view of the delivering device of the car. Fig. 6 is a vertical longitudinal sectional view through the delivering device of the platform. Fig. 7 is a vertical sectional view of the receiving device of the platform. Fig. 8 is an end elevation of the same. Fig. 9 is a detail perspective view of a portion of a car provided with the actuating elements for controlling the trip mechanism on the receiving device of the platform. Fig. 10 is a detail perspective view of the vertical block in which the trip shaft is interchangeably mounted.

The car A herein illustrated is provided with the usual door opening B and exteriorly of the car and mounted adjacent to one side of the door opening and near the top thereof is a receiving device 1 which consists of a swinging arm 2 pivoted at 3 to the car, so that it may freely swing in a horizontal direction.

Fixed to the car is a guide block 4 having a lug 5, in which is formed a guide opening 6, which slidably receives a guide rod 7. This rod is mounted at 8 to the arm 2 of the receiving device and, as shown, the rod is surrounded by a spring 9 whose ends are respectively interposed between the lug 5 and the arm 2, so that under the normal action of the spring, the arm tends to move in the direction of the door opening of the car. In this manner the receiving device may be made to lie in a relatively compact and flat manner against the side of the car

when not in use, so as not to form an obstruction to objects that may be within striking distances of the car.

A coöperating gripping arm 10 is pivoted to the arm 2, and as shown, said pivoted arm is provided with a gripping passage 11 through which an arcuate guide rod 12 of the arm 2 extends. The guide rod is threaded at its upper end and mounted thereon is an adjusting nut 13 and interposed between the nut and the arm 10 is a spring 14 under the action of the latter serving to cause the arm 10 to normally move into coöperating clamping relation with the said arm 2.

In order to provide means for holding the arm 10 in a receiving position relative of the arm 2 when the receiving device is set in the position shown in Fig. 1, and to further employ such means that may be directly actuated by the bag when it is received from the delivering device of the platform, I employ a keeper 15 pivoted at 16 to the arm 2 and provided with a portion 17 which is adapted to engage in a recess 18 in the arm 10 and thereby hold the arm against the action of the spring 14. The said keeper is provided with a tail 19, by which it may be readily set manually when desired. A spring 20 extends longitudinally over the upper surface of the arm 2, and as shown, one end of the spring is fixed to said arm, as at 21, and beyond such point the spring is slightly spaced from the arm so that it may be moved with relation thereto and the free end of the spring is then extended through a passage 22 in the arm 2 and then engaged directly against the tail 19 of the keeper 15. It is thus evident that when that portion of the spring which lies normally above and in spaced relation to the arm 2 is depressed through its engagement with the bag as the latter is received from the delivering device of the platform or said free terminal of the spring will be moved and motion will be imparted to the keeper, so as to release the said portion 17 thereof from the recess described in the arm 10.

The delivering device which is mounted on the platform C shown conventionally in Fig. 1, consists of a main standard 23 which is connected as at 24, to a relatively short fixed standard 25 which rises from the platform. The upper end of the standard 23 is bifurcated at 24 and pivoted between the branches 25 of such bifurcation is a gripping arm 26. This arm overlies a fixed arm 27 carried by the standard 23. The pivoted arm is provided preferably with one or a plurality of anti-friction bodies 28, such as rollers that are mounted in the arm so as to freely revolve and which are adapted to render the bag 3 for removal on the application of slight pull thereon by the receiving device of the car during the receiv-

ing operation. The arm 26 is provided with a tail 29 having a passage 30 therein which receives an arcuate guide 31. This guide is fixed to the standard 23 and above the tail 29 the guide is threaded for the reception of an adjusting nut 32. Interposed between the tail 29 and the standard 23 and surrounding said arcuate guide rod is a spring 33. Under the action of the spring the arm 26 is normally held in operative clamping position relative of its companion arm 27. At this time it is stated that the receiving device of the car is constructed with such regard to the delivering device of the platform that will permit the arms 2 and 10 to respectively pass above and below the arms 26 and 27 of the delivering device of the platform. The delivering device of the car consists of an arm 34 pivoted to the opposite side of the door opening B and preferably at a point near the bottom thereof. This arm is somewhat similar to the arm in the receiving device of the car, and as illustrated it is provided with a co-acting pivoted gripping arm 35. The arm 34 has an arcuate guide rod 36 which extends through a passage 37 in the arm 35, and as shown said rod is threaded at its upper end to accommodate an adjusting nut 38. A spring 39 is interposed between the arm 35 and the adjusting nut and it surrounds the guide rod and under the action of the spring the arm 35 is normally held in proper clamping position with relation to the arm 34.

A retaining device 40 in the form of a pivoted lever mounted in the door opening of the car is employed for the purpose of engaging the arm 34 and thereby holding the same in a delivering position. The arm 34 is provided with a pivoted guide rod 41, which slidably extends through a guide block 42 mounted at one side of the car. Said rod is surrounded by a spring 43 and under the action of the latter the arm 34 is adapted to normally move in the direction of the door opening.

The receiving device of the car must necessarily be held at right angles to one side of the car when in a receiving position and in view thereof a pivoted retainer or lever 44 may be engaged therewith. This lever is identical with the form of lever described at 40 and employed for the purpose of holding the delivering device of the car in operative delivering position. The receiving device of the platform comprises a standard 45 bifurcated at 46 and pivotally supporting a gripping arm 47. The standard 45 supports a horizontal gripping arm 48 which underlies the pivoted arm. An arcuate guide rod 49 is fixed to the tail 50 of the arm 47, and it is slidably through a slot 51 formed in the standard 45. A spring 52 surrounds said rod and its ends are respec-

- tively engaged against the standard 45 and the tail 50, so that under the action of the spring the arm 47 will tend to normally move in a direction of its companion arm 48.
- 5 The tail 50 of the arm 47 is provided with a continuous horizontal passage 52'. At the bottom of the standard is formed a passage 53 having its lower walls provided with relatively offset depending depressions 54 and 55, which are alined with similar depressions 56 and 57 formed in the lower wall of a recess 58. This recess is formed in a vertical block 58' which rises from the platform. A trip shaft 59 is interchangeably 10 mounted in the depending offset portions in the lower walls of the slots 53 and 58. This shaft is provided with a locking branch 60 having at its free end a pin 61 provided with oppositely extending branches 62 and 63.
- 15 20 The opposite end of the shaft is provided with an angular branch 64.

The mechanism herein employed may be advantageously relied upon for the handling of mail matter from cars that are intended 25 to travel on a road bed having a single track structure. For this reason, it is necessary that means be employed for rendering the receiving means of the platform active for the receipt of a bag irrespective of the direction 30 of movement taken by the car. For this reason the car is provided with indentical trip levers 65 and 66 which are pivoted within the car and which are provided at their lower ends with controlling branches 35 67 and 68 that are slidable in guide passages 69 formed in the side of the car.

Now that the construction of the apparatus is clearly described a brief description of its operation may be had, as follows:

40 Assuming that a bag is to be collected by the receiving means of the car and that a bag is to be delivered from the delivering means of the car to the receiving means of the platform when the car is traveling in the direction 45 of the arrow *a* shown in Fig. 1, a mail bag *D* may be placed between the arms 26 and 27 of the delivering device of the platform and the receiving device 1 of the car may be set so that its arms 2 and 10 are 50 adapted to respectively move above and below said arms 26 and 27 and to straddle the bag. As soon as slight pressure of the bag is brought to bear against the flat spring 20 of the arm 2, the keeper 15 will be instantly 55 controlled and both arms will be moved into coacting gripping positions against the bag and consequently moved entirely from between the arms 26 and 27. The bag to be delivered to the receiving device of the platform is indicated at *E*, and the delivering device of the car is set so as to effectually grip the bag when the device is in a delivering position. The device is constructed 60 with such regard to the arms 47 and 48 that 65 will permit the bag *E* to freely pass into the

space between the arms 47 and 48 as the car approaches the receiving device of the platform. The controlling levers that are mounted within the car are first actuated so that the branch 68 of the lever 66 is projected for a distance where it will engage the branch 64 of the trip shaft 59. The extension 63 of the pin 61 is extended into its receiving passage in the tail 50 of the arm 47. Through this arrangement it is seen 70 that as soon as the portion 64 is struck by the branch 68 the shaft 59 will be moved and its pin 61 will be released from the arm 47 and the latter will be instantly moved into co-operative gripping engagement with 75 the arm 48 so as to confine the bag, as will be understood.

Various changes in the form, proportion and the minor details of construction may be resorted to without departing from the 80 principle or sacrificing any of the advantages of this invention as claimed.

I claim:—

1. The combination with a delivering device having relatively movable bag gripping portions, of a receiving device having companion relatively movable gripping portions operable for the passage of the gripping portions of the delivering device therebetween.

2. The combination with a delivering device having relatively movable bag gripping portions, of a receiving device having companion relatively movable gripping portions operable for the passage of the gripping portions of the delivering device therebetween, and means for normally holding said portions of the receiving device spaced relatively when the device is in receiving position.

3. The combination with a delivering device having relatively movable bag gripping portions, of a receiving device having companion relatively movable gripping portions operable for the passage of the gripping portions of the delivering device therebetween, means for normally holding said portions of the receiving device spaced relatively when the device is in receiving position, and means for rendering the said portions active to a gripping engagement with the bag on receipt of the bag between said portions.

4. In mail bag receiving and delivering mechanism, a receiving device having relatively movable gripping portions, means for moving said portions, means for holding said portions against the action of the moving means, a delivering device adapted to pass between the gripping portions of the receiving device, and means for releasing 120 the holding means automatically on predetermined relative positions of the receiving device and the delivering device.

5. In mechanism of the character described, a receiving device having relatively 130

movable gripping portions, means for moving the portions relatively into gripping positions, means for normally holding the portions against the action of the moving means, delivering mechanism on the car adapted to pass between the relatively movable portions of the receiving device, and means on the car controlling the holding means of the receiving device to render the

gripping portions of the receiving device active under the action of the moving means of said device. ¹⁰

In testimony whereof I affix my signature in presence of two witnesses.

ROBERT J. HARLEY.
